UNITED STATES PATENT OFFICE.

FRED A. SHOMAN, OF MILWAUKEE, WISCONSIN, ASSIGNOR TO THE PHINNEY ENGINEERING CO., OF CHILlicothe, OHIO, A CORPORATION OF OHIO.

MACHINE FOR SNIPPING BEANS.

1,102,808.

Specification of Letters Patent.

Patented July 7, 1914.

Application filed March 27, 1909, Serial No. 486,282. Renewed March 10, 1913. Serial No. 753,418.

To all whom it may concern:

Be it known that I, FRED A. SHOMAN, a citizen of the United States, residing at Milwaukee, in the county of Milwaukee and 5 State of Wisconsin, have invented a new and useful Machine for Snipping Beans, of which the following is a specification.

This invention relates to machines for snipping beans, and it consists in the novel 10 construction and arrangement of its parts, as hereinafter shown and described.

The object of the invention is to provide a machine adapted to remove the end portions of beans prior to canning the same, 15 which operation of removing the end portions is usually referred to as "snipping".

The parts of the machine are so arranged that the beans in tangled state or condition may be fed to the same, and the said machine is provided with means for positioning and straightening out the beans prior to 20 passing the same between shearing knives for removing the end portions as indicated.

In the accompanying drawings: Figure 1 25 is a vertical longitudinal sectional view of the machine; Fig. 2 is an end view of the same; Fig. 3 is a side elevation of the same; Fig. 4 is a plan view of an endless belt, and adjacent parts, used upon the machine; Fig. 30 5 is a transverse sectional view of the said belt and adjacent parts. Fig. 6 is a top plan view of a portion of the machine.

The machine consists of a stand or frame 1, the upper portion of which supports the 35 upper end of an inclined trough or trunk 2.

An endless elevator or belt 3 is mounted for orbital movement about the bottom of the trunk 2, and preferably is in the form of a continuous chain, which passes around a 40 sprocket wheel 4, journaled at the lower portion of the trunk 2 and around a sprocket wheel 5, fixed to a shaft 6, journaled for rotation at the upper portion of the said trunk 2. A drum 7 is journaled for rotation 45 upon the upper portion of the frame 1 below the shaft 6 and is provided upon its periphery with a series of pockets 8. A

drum 9 is journaled for rotation upon the upper portion of the frame 1 below the 50 drum 7, and is provided upon its periphery with a series of pockets 10. A cloth or other flexible material 11 is secured at its upper edge portion to the upper extremity of the trunk 2 and lies loosely upon the 55 upper portions of the drums 7 and 9 or at

the extremities of the side walls of the pockets 8 and 10 located upon the said drums. A shaft 12 is journaled for rotation at the upper portion of the frame 1, as is also a shaft 13. The said shafts 12 and 13 are 60 located approximately at the same elevation, and the shaft 12 is provided with a sprocket wheel 14, while the shaft 13 is provided with a sprocket wheel 15. A continuous chain belt 16 is mounted for orbital movement about the sprocket wheels 14 and 15. The upper run of the chain 16 is located below the drum 9, and the said chain is provided upon its outer side with a series of cups 17. Each cup has a relatively long 65 side 18, and a relatively short side 19, the short side of one cup coming in contact with the long side of the adjacent cup when the said cups are upon the upper run of the said chain 16. The cups 17 are open at their 70 ends and are approximately oblong in plan. A table 20 is located upon the frame 1 below the lower run of the chain 16, and is adapted to be engaged by the edges of the longer sides 18 of the cups 17 as the said cups move 75 along the lower run of the chain 16. One end of the said table 20 is continued into a shield 21, which extends approximately concentrically with relation to the shaft 13, and the inner face of which is also adapted 80 to be engaged by the edges of the longer sides 18 of the cups 17 as the said cups pass along the said shield. The table 20 is provided at its end portions with openings 22 and 23. A brush 24 is located above the upper run of the chain 16 and is positioned 85 behind the drum 9. A strip of canvas or other flexible material 25 is located behind the brush 24 and is also positioned above the upper run of the chain 16. An approximately inflexible bar 26 is also located above the upper run of the chain 16 and is positioned 90 behind the canvas strip 25.

A shaft 27 is journaled for rotation under the intermediate portion of the table 20 and is provided upon its inner end with a bevelled pinion 28. The said pinion 28 meshes with the pinions 29 and 30 which are located at opposite sides of the pinion 28, and which are attached to the stub shafts 31 and 32 105 respectively. A pulley 33 is mounted upon the end portion of the shaft 31, and an endless belt 34 passes around the said pulley 33 and an idle pulley 35 journaled for rotation 110 at the opposite side of the machine. The

upper run of the belt 34 enters the opening 22 provided in the table 20. A pulley 36 is fixed to the shaft 32 and an endless belt 37 passes around the said pulley 36 and an idle pulley 38, journaled for rotation at the opposite side of the frame of the machine. The upper run of the belt 37 enters the opening 23 provided in the table 20. Supporting means are positioned under the upper runs of the belts 34 and 37 to hold the same substantially in the same plane as that in which the table 20 lies. An adjustable gage 39 is mounted upon the frame 1 over the upper run of the endless belt 34 with its lower edge approximately in contact with the upper surface of the upper run of the said belt, and the said gage 39 is positioned beyond the ends of the cups 17. A similar gage 40 is mounted in a similar manner over the upper run of the endless belt 37, but beyond the opposite ends of the cups 17.

Any suitable arrangement of endless chains or belts may be provided for transmitting movement from the shaft 27 to the shafts 12 and 6, and the shafts of the drums 7 and 9. One manner in which the said endless belts may be arranged is illustrated in Fig. 3 of the drawings, in which it will be seen that a sprocket wheel 41 is mounted upon the shaft 27, and a sprocket wheel 42 is mounted upon the shaft 6. Sprocket wheels 43 and 44 are also mounted upon the shafts of the drums 7 and 9 respectively, and an endless sprocket chain 45 passes around and over the sprocket wheels 41, 42, 43 and 44. Also it will be seen that a sprocket wheel 46 is mounted upon the shaft 12, and a sprocket wheel 47 is mounted upon the shaft of the drum 9. An endless sprocket chain 48 passes around the sprocket wheels 46 and 47.

A revolving cutter 49 is mounted upon the shaft 27 in a plane between the plane of the inner face of the gage 39 and the adjacent ends of the cups 17. A rotary cutter 50 is mounted above the cutter 49 and is held in contact with the same by means of a coil spring 51 which bears at one end against the cutter 50, and at its opposite end against a fixed stop provided upon the frame 1. A cutter 52 is mounted upon the shaft 12 and is located in a plane between the inner face of the gage 40 and the adjacent ends of the cups 17. A rotary cutter 53 is mounted upon the frame 1 below the cutter 52 and is held toward the same by means of a coil spring 54, which bears at one end against the side of the cutter 53, and at its opposite end against a fixed portion of the said frame 1.

From the above description it is obvious that as the shaft 27 rotates (which may be accomplished by any suitable mechanical expedient) through the beveled pinion 28 ro-

tary movement is transmitted to the shafts 31 and 32, which rotary movement on the part of the said shafts is in the opposite direction with relation to each other. As the said shafts 31 and 32 rotate the pulleys 33 and 36 also rotate, and the endless belts 34 and 37 are moved longitudinally but in opposite directions. At the same time rotary movement is transmitted from the shaft 27 through the chain 45 or its equivalent to the shaft 6 and to the drums 7 and 9. The said shaft 6 rotates in the same direction as the drums 7 and 9. Also rotary movement is transmitted from the shaft of the drum 9 to the shaft 12.

The beans to be snipped are fed to the lower portion of the endless conveyer 3 and are carried up by the same along the trunk 2, and when they arrive at the upper end of the said conveyer they fall upon the periphery of the drum 7 and enter the pockets 8 provided thereon. Thus the beans which pass up the trunk 2 in a relatively tangled state are partially separated as they fall upon the periphery of the drum 7 and are also, to a limited extent, straightened out, or longitudinally arranged with relation to each other. From the periphery of the drum 7, the beans then fall upon the periphery of the drum 9 and into the pockets 10, mounted upon the periphery thereof. At this stage the beans are further separated and straightened transversely with relation to the machine. From the drum 7 the beans fall into the cups 17 which are moving under the lower portion of the drum 9 and along the upper run of the chain 16, and thus the beans are further separated and still further aligned or positioned transversely with relation to the machine. The beans are then carried by the cups under the brush 24, the bristles of which are downwardly disposed, and should portions of the beans project above the upper edges of the said cups, they are engaged by the bristles of the brush 24, which has a tendency to push the beans down within the cups. If however the action of the brush 24 is not sufficient to force the beans down, the projecting portions of the beans come in contact with the flexible strip 25, and the weight of the said strip has a tendency to force the projecting portions of the said beans down below the upper edges of the cups 17. If however the projecting portions of the beans still refuse to move down below the upper edges of the cups 17, they come in contact with the angularly disposed bar 26, and the said bar forces the beans which have projecting portions out beyond the ends of the cups 17. Those beans that have been properly positioned in the cups 17 as above indicated are carried under the upper end portion of the shield 21 and along the inner face of the same, and

as the said cups assume inverted positions the beans come in contact with the inner face of the shield and eventually pass upon the upper surface of the table 20. The beans 5 are carried along the upper surface of the said table by the relatively longer sides 18 of the said cups 17, and are brushed upon the upper run of the endless belt 34. As the said belt is moving transversely with 10 relation to the movement of the belt 16, the beans moved upon the upper run of the said belt 24 move longitudinally with the upper run of the said belt so that their end portions are brought in contact with the inner face of the gage 39. The said gage 15 39 checks further longitudinal movement on the part of the beans, but the longer sides 18 of the cups 17 continue to sweep the beans transversely across the upper run of the belt 20 34, and the said beans are then carried upon the intermediate portion of the upper surface of the table 20. As the beans are carried along the said intermediate portion of the said table they eventually come in contact with the upper edge of the rotating cutter 49 and below the edge of the cutter 50. The said cutters 49 and 50 sever the 25 projecting ends of the beans at one side of the belt 16. The beans continue in their movement along the table 21 until they arrive at the upper run of the belt 37, and the said beans are then moved longitudinally in the opposite direction from that in which they are moved when in position 30 upon the upper run of the belt 34. Thus the opposite ends of the beans are brought in contact with the inner face of the gage 40, which checks further longitudinal movement on the part of the beans. The beans 35 are continued in their movement transversely across the upper run of the belt 37 by the longer sides 18 of the cups 17, and eventually the projecting ends are brought between the cutters 52 and 53, 40 which sever the projecting ends in a manner similar to that described with respect to the operation of the cutters 49 and 50 upon the opposite end portions of the beans. The beans, with their ends removed or 45 snipped, as above described, are then carried to the end of the table 20, from which they may fall into suitable receptacles provided for their reception. By such an arrangement it will be seen that a machine is provided to which the beans may be fed in a tangled condition or state, and during the passage of the beans through the machine they are straightened out and positioned, and separated prior to presentation to the 50 snipping knives, which are so located as to remove the end portions from the beans in the manner as indicated, thereby rendering the beans ready for canning or other purposes.

Having described my invention, what I 65 claim as new, and desire to secure, by Letters Patent, is:—

1. A machine for snipping beans comprising a carrier mounted for orbital movement and having cups to receive the beans, a table 70 over which the lower run of the carrier passes, means for supplying the beans to be snipped to said cups while the latter are on the upper run of said carrier, endless belts having upper runs located in the plane 75 of the table, said belts moving in directions opposite to each other, and cutters located behind each belt.

2. A machine for snipping beans comprising a carrier mounted for orbital movement, 80 a table located below the carrier, a bean feeding device arranged above the carrier, endless belts having upper runs located in the plane of the table, means for moving the said belts in opposite directions, an adjustable gage mounted above the upper run of each belt, and a cutter located behind each belt.

3. A machine for snipping beans comprising an endless carrier mounted for orbital 90 movement, a table located below the carrier, means for projecting the beans alternately beyond the opposite sides of the carrier, means for removing the projecting ends of the beans, a drum located above the carrier 95 and having pockets provided upon its periphery, an elevator for supplying beans to the drum, and a flexible material resting upon the upper portion of the drum.

4. A bean snipper comprising a main carrier adapted to move the beans and having an upper run and a lower run, means for supplying beans to the upper run of said carrier, a belt adapted to move the beans transversely of the lower run of the main 105 carrier, and a cutter for removing the ends of the beans arranged on that side of the main carrier toward which the beans are moved by said belt.

5. A bean snipper comprising a main carrier adapted to move the beans and having an upper run and a lower run, means for supplying beans to the upper run of said carrier, a belt adapted to move the beans transversely of the lower run of the main 110 carrier, a gage against which the beans are carried by said belt, and a cutter for removing the ends of the beans arranged on that side of the main carrier toward which the beans are moved by said belt.

6. A bean snipper comprising a main carrier adapted to move the beans and having an upper run and a lower run, means for supplying beans to the upper run of said carrier, a primary belt which operates to move the beans transversely of the lower run of the main carrier in one direction, a secondary belt which operates to move the beans 125

transversely of the lower run of the main carrier in the opposite direction, gages against which the beans are moved by said belts, and cutters past which the opposite ends of the
5 beans are pivoted by the main carrier after the same have been moved transversely by said belts against said gages.

In testimony that I claim the foregoing as my own, I have hereto affixed my signature in the presence of two witnesses.

FRED A. SHOMAN.
